EVAPORATOR DOOR

Clifford Brooks Stevens, Fox Point, and John Hughes, Jr.,
Whitefish Bay, Wis., assignors to Gibson Refrigerator
Company, Greenville, Mich., a corporation of Michigan

Application June 7, 1955, Serial No. 36,422

Term of patent 7 years

(Cl. D67—3)

Fig. 1 is a front view in elevation of an evaporator door as employed within a refrigerator showing our new design, Fig. 2 is a top plan view,

Fig. 3 is a vertical enlarged sectional view, the section being taken as indicated at line 3—3 of Fig. 1,

Fig. 4 is a detail enlarged sectional view, the section being taken as indicated at line 4—4 of Fig. 1, and

Fig. 5 is a broken enlarged sectional view, the section being taken as indicated at line 5—5 of Fig. 1.

We claim:

The ornamental design for an evaporator door, as shown.
